SHAVER WITH HAIR RAISING BRUSH

John T. Scully, New York, N. Y.

Application May 26, 1950, Serial No. 164,316

16 Claims. (Cl. 30—34)

My invention relates to shavers, hair cutting machines in which relatively movable members cooperate to shear or clip off hairs, such machines being sometimes referred to as hair clippers, dry shavers, shaving machines and the like and are employed without the use of shaving cream, soap lather or other beard emollients.

Reference is made to my co-pending applications for improvements in shavers (titles changed to: Brush Attachments for Shavers), Serial No. 120,783, filed October 11, 1949, and Serial No. 132,547, filed December 12, 1949.

Among the objects of the present invention are the provision of an improved combination of facilities for dry shaving, the provision of a compact and efficient arrangement of a hair up-raising brush and a shearing head or heads, the provision of an improved hair up-raising brush for cooperative action with the shearing head or heads in the shaving operation, the provision of improved seating means for the brush adjacent the seat for the shearing head or heads, the provision of improved and compact means mounting a hair up-raising brush movable towards or away from a shearing head, the provision of means for spacing a hair up-raising brush adjustably from a shearing head, the provision of an improved arrangement of hair up-raising brushes spaced by a shearing head or heads, and to provide a general improvement in the shaving operation in a simple and efficient manner. Other objects will become apparent from the description taken in connection with the accompanying drawing.

Referring to the drawing and in which similar reference characters refer to similar or corresponding parts throughout the several views:

Fig. 1 is a side elevation of the head end of a shaver embodying the invention in one form; Fig. 2 is a side end view of the shaver head end shown in Fig. 1 with a part broken away to show pertinent parts in end view; Fig. 3 is an enlarged top plan view of the head end of the shaver shown in Fig. 1; Fig. 4 is a side elevation of a parts shown in Figs. 1, 2 and 3; Fig. 5 is an enlarged cross-sectional view taken on the line 5—5 of Fig. 1 with parts omitted and with the shaver casing broken away to show fastening parts partly in section and elevation; Fig. 6 is an enlarged fragmentary side end elevation with parts broken off to show an interchange of parts; Fig. 7 is an enlarged fragmentary side end elevation of a modification of the head end with parts broken away for clarity of view; Fig. 8 is an enlarged side elevation, with a part broken away to show fastening details, of a further modification of the head end of the shaver; Fig. 9 is a bottom elevational view on a smaller scale of a part shown in Fig. 8 detached from the shaver; Fig. 10 is a side end elevational view of the head end of the shaver shown in Fig. 8, with a part broken off to show relationship of parts, and with parts broken away to show fastening details; Fig. 10A is a front side view in elevation of a modification of parts, with a part broken away to show a part in elevation and a part in section; Fig. 11 is a greatly enlarged side end elevation, with parts broken off to show parts in end elevation and in cross-section, with parts

broken away to show fastening details, of the head end of the shaver further modified; Fig. 12 is a side elevation, with parts broken away to show fastening details, of the head end shown in Fig. 11; Fig. 13 is a greatly enlarged longitudinal sectional, view with parts shown in elevation, of a brush mount shown in Figs. 11 and 12 and with a movable part shown in a relatively changed position.

As I have pointed out in my hereinbefore referred to copending applications, I have found utility in the combination in a shaver of a shearing head and a hair up-raising brush having a longitudinal series of flexible bristles extending lengthwise with the shearing head, the bristles being suitable for skin engagement and being suitably spaced from the hair-receiving openings in the shearing head so as to avoid blocking the entrances of the openings when the bristles are flexed towards the shearing head as the shaver is moved on the skin with the brush bristles and the shearing head in simultaneous engagement with the skin during the shaving operation. Principally, the brush bristles are useful for dislodging or sweeping from the beard or skin grit or flint-like particles to minimize or prevent damage to the shearing or cutting members of the shearing head, for tautening the skin in advance of the shearing head, especially in the localized areas closely adjacent to or immediately ahead of the shearing head and for, importantly, dislodging, erecting or deflecting, or otherwise disturbing the positions of the hairs on the skin, particularly hairs lying close to the skin in curled or slanted positions, to facilitate the entrance 15 of such hairs into the shearing head, and for, also importantly, lifting short hairs in the direction opposite to their direction of growth to position these short hairs in a more erect position ahead of the shearing head and for similarly lifting and bending backwardly longer hairs so 20 that when released by the brush bristles these longer hairs will spring back towards the shearing head to facilitate their entrance therein and to present themselves in more erect positions to the shearing members.

The present invention is shown herein as including 25 parts, for purposes of illustration, but not limitation, of an otherwise well known and commercially presented shaver of a type commonly called a multiple shearing head shaver.

Referring more particularly to the drawing herein: 30 The shaver shown in Figs. 1—5 inclusive, has the usual casing-handle housing the electric motor, the casing being longitudinally divided into sections oppositely disposed and fastened together by screws of which an upper set 20 are shown. At the top or head end of the casing handle, spaced shearing heads 21 and 22 are detachably seated 35 with their ends closed off by pocket members connected to each other by expansion springs of a whisker clippings catching device 23 detachably secured to the shaver in the well known manner. Shearing heads 21 and 22 are 40 of similar construction and comprise outer shear members 24, having hollow portions extending up from base block portions, which on their top portions are longitudinally channelled to present on opposite sides of the channels two rows of hair-receiving slots 25 and 26 which 45 rows are transversely spaced from each other by longitudinally extending webs of solid metal, slots 25 being longitudinally offset to slots 26 and extending from the top or skin engaging portions of the members down into the side portions thereof, and slots 26 extending in the 50 opposite direction and down into the side walls of the channels. Slots 25 and 26 form the combing and shearing bars in the outer shear member for shearing cooperation with the movable inner cutters 27 which are transversely slotted as at 28 to form rows of cutter bars to 55 coact with the shearing bars in the outer member. The inner cutter is held spring pressed upwardly against the 60 inner surface of the outer member by spring devices 65 to 70

housed in and projecting upwardly from the base blocks. The shearing heads are detachably held seated on the head end of the shaver between casing wall portions thereof by fastening devices made up of U-shaped, bell-like sided clamp springs and screws 29, the screws extending into sockets in the casing with the heads of the screws holding the clamp springs sides spread apart with edges of the sides of the clamp springs engaged into slots in the sides of hollow portions of the outer shear members, these fastening devices being located substantially centrally of the lengthwise dimensions of the heads. The base block portions of the shearing heads are centrally provided with holes therethrough and through which extend oscillator bars 30 which extend into the inner cutters, in holes therein, to engage and longitudinally reciprocate the inner cutters as the bars are oscillated or rocked by the electric motor. Between shearing heads 21 and 22 and in a central head seat of the shaver is seated a hair up-raising brush 31 having a longitudinal series of flexible bristles 32 for engaging the beard and skin simultaneously with the engagement of the beard and skin by the shearing heads during the shaving operation to cooperate with whichever of the heads becomes the trailing head according to the direction in which the shaver is moved on the skin. Brush 31 is preferably of the tufted type, the bristles being stapled in tuft forms in shallow sockets forming a longitudinal row in a rectangular bristle holding block which on its bottom face has a positioning slot 33 extending transversely and which receives a ridge-like transverse positioning shoulder, not shown, in the brush seat on the head end of the shaver. On transversely opposite sides and centrally disposed longitudinally, brush 31 has fastening member receiving slots or grooves 34 into which the side edges of the spring clamps of the fastening devices 29 project to engage 31 and hold same in its seat similarly as the heads are held in their seats. Slots 34 are shown herein as wheel cut, or ground, grooves. Centrally disposed in the bristle holding block of brush 31 and extending upwardly therein from the bottom face thereof is an oscillator bar-receiving hole 35 which is deep enough and otherwise large enough to permit the middle oscillator bar to be rocked back and forth freely relatively to the brush and together with the side oscillator bars by the electric motor. Brush bristles 32 extend upwardly beyond the shearing bars of the outer shearing member of the shearing heads and are substantially centrally disposed between, or symmetrically spaced from, the shearing heads. The bristles may be of any suitable material, natural or synthetic, and are preferably closely enough grouped in the individual tufts and the tufts close enough together to engage all hairs within the longitudinal limits of the bristle formation to make a clean sweep, so to speak, of the beard and skin areas in the limits.

Referring particularly to Fig. 5, it will be observed that if the shaver is moved on the skin in a direction to the reader's right shearing head 22 will be the leading head and bristles 32 will be flexed in the direction of the trailing head as indicated by the arcuate dash line directed from the bristles to the reader's left, and it will be noted particularly that, when so flexed, the bristles are still spaced from the sides of the trailing head by a suitable space indicated at 36 so as not to block the entrances of the hair-receiving openings or slots in the head; similarly, it will be noted, when the shaver is moved on the skin to the reader's left the bristles will be flexed in the direction towards the now trailing shearing head 22 as indicated by the arcuate dash line directed from the bristles to the reader's right and that, when so flexed, the bristles are still spaced from the sides of the trailing head 22 by a suitable space indicated at 37 so as not to block the entrances of the hair-receiving slots in 22. It is well known that the strength of beard hairs and the shaving habits of persons are not the same for all individuals who shave and, therefore, in commercial presentations,

brush 31 may be presented in the forms of different models, one having relatively longer bristles so that spaces 36 and 37 will be narrower for the daily shaver's very short beard growth, and another having relatively longer bristles so that spaces 36 and 37 will be wider for the longer beard growth of persons who shave less frequently, for example, once a week. As shown herein, spaces 36 and 37, as a general rule, are wide enough to allow beard hairs of several days beard growth to be entirely released or freed from the bristles 32 before the trailing shearing head reaches a given hair to permit the freed hairs to spring back towards said shearing head to provide opportunity for the shearing members to shear the hairs during their spring back and while in a relatively more erect position; the person who shaves daily can attain the same results with his shorter beard by moving the shaver relatively faster on his skin to compensate for the time element in the spring back of his hairs. It is also well known that the sensitivity of the skin varies in individuals and, therefore, I prefer to provide a not unnecessarily excessive number of bristles in the tufts, that is, in the individual tufts. The material of which the bristles are composed and the thickness or diameter of the individual bristles may be related to the exposed lengths of the bristles, for example, but not by way of limitation, in some instances nylon brush bristles may be the material and the diameter of the filament may be .004 of an inch; in other instances the same material may be used and the diameter of the filament may be .005 of an inch.

Shearing heads 21 and 22 have substantially the same dimensions and may be seated in interchanged positions, one in the seat of the other and fastened therein by 29; the stiff bristle holding block of 31 has substantially the same width as the width of either shearing head and may have substantially the same length or may be somewhat shorter depending upon whether 23 has inner face ribs or other projections on the inner face; in instances where the bristle block may be shorter than the heads, the spacing of the ends from 23 will be large enough to avoid catching hairs and pulling them. Therefore, it will be observed that the user may change the arrangement of brush and heads, for example, by seating the brush and head 22 in interchanged positions as shown in Fig. 6, or that the shaver may be presented commercially in a less expensive form, initially, by substituting a brush for a head as shown in Fig. 7, both brushes being similar to 31.

In the modification shown in Figs. 8, 9 and 10, the shaver (otherwise similar to the shaver shown in Figs. 1-5 inclusive) shown, in addition to the side shearing heads and the brush between, is provided with a hair up-raising brush 38 positioned on the side of the casing, outside thereon, with the flexible bristles 39 of the brush disposed spaced from and alongside a side of shearing head 21a and extending upwardly therebeyond a distance substantially the same as the distance therebeyond that bristles 32a, between heads 21a and 22a, extend. Brush 38 has its stiff, bristle holding, block fastened on a ledge 40 of a brush supporting frame by detachable screws 41 and from the ledge a pair of ledge supporting arms 42 extend downwardly and the outer marginal edges of 42 are inturned to provide casing-abutting feet or leg portions 43 which hold the remainder of the frame out of engagement with the casing to bridge over curved surfaces or corrugations. The frame is fastened to the casing by screws 20a (which are relatively longer than and substituted for screws 20, Fig. 1) and provides a steady support for the brush. Bristles 39 may be of any suitable material of any suitable filament diameter and are relatively longer than the bristles 32a; in the form as shown, bristles 39 are preferably nylon brush bristles having a filament diameter of .005 of an inch; and, as will be observed, upon particular reference to Fig. 10, if the shaver is moved on the skin in a direction to the reader's left, bristles

39 will be flexed in the direction of head 21a as indicated by the arcuate dash line directed from the bristles toward 21a and that, when so flexed, the bristles are still spaced from the hair-receiving slots and shearing bars of 21a so as not to block the entrances of the slots and to provide the space 44 between the tip ends of the bristles when flexed and the hair-receiving slots. In some instances, the brush supporting frame may be modified as shown in Fig. 10A and in which ledge 40a of the frame may be shorter and have on its front edge spaced upwardly bent tongue portions 45 and to which may be fastened, by screws 41a extending into the bristle holding block thereof, a substituted brush 31a, of similar dimensions and similar in other characteristics to previously described brush 31, the distance from the bottoms of the brushes to the tops of the bristles in Figs. 4, 10 and 10A being substantially the same and the ledge angle of the frame in 10A being compensatory to the relative difference in lengths of bristles between 31a and 38.

Referring again to Figs. 8, 9 and 10, it will be clear, since it is common and best practice, in dry shaving, to move a shaver on the skin in alternately opposite directions during the shaving operation, that, when the shaver is moved on the skin in the direction to the reader's right, bristles 32a, of the brush disposed between shearing heads 21a and 22a (Fig. 10), will erect beard hairs for entrance into the slots of shearing head 21a substantially similarly as will bristles 39 of the side brush when the shaver is moved on the skin in the direction to the reader's left.

In the modification shown in Figs. 11, 12 and 13, the shaver (otherwise similar to the shaver in Fig. 1) is provided on opposite sides thereof with adjustably positioned hair up-raising brushes having flexible bristles 39a and 39b. These brushes are similar and the supporting and adjusting mechanism of one is similar to the adjusting and supporting mechanism of the other. The mechanism comprises a base portion or member 46 having opposite marginal ends inturned to abut the casing; oppositely disposed end bearing blocks 47 are secured to 46, each by a pair of longitudinally offset screws 48 extending into the blocks on opposite sides of centre of the blocks; an intermediate or central bearing block 49 is secured to 46 by spaced screws 50, and in these aligned blocks, extending therethrough, are longitudinally directed, coaxial, cylindrical holes receiving, for slidable movement therein, stepped cylindrical rods 51 and 52, the large cylindrical ends of the rods being received in end blocks 47, the opposite and smaller cylindrical ends of the rods being received in block 49. On their upper sides, blocks 47 are provided with longitudinal slots into which holding pins 53 project from the large end portions of 51 and 52 to coat with the side walls formed by said slots to prevent rotation or turning movement of the bars. Between the large and small ends of 51 and 52 are intermediate cylindrical portions which are externally threaded for a suitable portion of their lengths, the threaded portion of 51 being a right hand thread in cooperative threaded engagement with an internally threaded block 54 and the threaded portion of 52 being a left hand thread in cooperative threaded engagement with an internally threaded block 55; blocks 54 and 55 being on opposite sides of block 49 and being connected to the brush carrying bars 56 by spaced screws 57 and secured against any tendency to turn thereon by pins 58 extending from 56 into 54 and 55; bars 56 have longitudinally spaced internally threaded holes 59 in threaded engagement with screws 41b extending from the bristle holding blocks of the brushes. Surrounding the intermediate portions of 51 and 52 between their large end portions and blocks 54 and 55 are compression springs 60 bearing in one direction against blocks 54 and 55 and in the opposite direction against

the annular shoulders or flanges at the inner ends of the large cylindrical portions of screw bars 51 and 52 to tighten the threaded connections between 51 and 54 on one hand and 52 and 55 on the other by tending 5 to force the screw bars 51 and 52 outwardly. Coil springs 60 are at all times under compression. The longitudinal central portion of bar 56 is, in each case, approximately as wide as the bristle holding blocks of the respective brushes, but at longitudinally opposite 10 marginal ends, these bars are wider, preferably, to provide inward projections or extensions having, preferably, spherically curved inner edges; these extensions serve as stops to abut suitable portions of the casing to limit inward movement of the brushes towards the shearing heads, the stops being indicated by 61. A relatively long pair of screws 20b connect the casing sections and fasten one of base members 46 on one side of the shaver; a relatively shorter pair of screws 20c, coaxially oppositely disposed to 20b, are screwed into 15 threaded holes in the casing and fasten the other of members 46 on the shaver. To adjust the position of the side brushes, the user will seize the ends of the brushes to manipulate the movement; as a side brush is pulled outwardly or pushed inwardly, as the case may 20 be, central block 49 and blocks 54 and 55 will help to guide the direction of pull or push. As a brush is swung outwardly screw bars 51 and 52, by their threaded connections with 54 and 55, are caused to slide longitudinally outwardly, their slide movement being guided 25 by the pins 53 and the slot walls in end blocks 47, the pins and walls also serving to prevent rotation of 51 and 52, and the outward slide movements of 51 and 52 lessen the compression of coil springs 60; because of the small threads on 51, 52, 54 and 55, for example, in the proportions of forty-eight threads, or, if desired, fifty-six threads, to an inch, the slide movement distance of 51 and 52 is very slight and, consequently, only a slight amount of coil spring compression is released, so that, while the compression of 30 springs 60 varies according to the distance a brush is moved in either direction, there is always sufficient compression to retain the brush in its adjusted position. Referring particularly to Fig. 11, the brush on the left side is shown in solid line adjustably positioned pulled laterally outwardly somewhat so that its bristles 39a, 35 when flexed by the skin, will be laterally spaced from the corresponding side shearing head by a space indicated by 64, between the tips of the bristles when flexed and the side of the shearing head, suitable for a beard growth of a person who, for example, shaves every 40 other day; to expose the shearing head to his vision to trim a mustache, the sideburns, shave near his nose, or dust out his beard before shaving the brush may be adjustably positioned retracted aside as shown by the 45 dotted outline 62; the brush may be turned down to the retracted aside position shown by dotted outline 63, its downward limit; the brush may be moved towards the shearing head until the stops 61 engage the casing and at this adjustment will have the same relative position 50 as the brush shown in solid line on the right side has and will be in its most tightly retained position. The brush on the right side is shown in solid line adjusted to its maximum closeness to the corresponding side shearing head so that its bristles 39b, when flexed by 55 the skin, will be spaced from the shearing head by a space indicated by 67, between the tips of the bristles when flexed and the side of the shearing head, suitable, for example, for a person who shaves daily; for longer hairs, beard or other body hair, the brush may 60 be adjustably positioned, for example, further out laterally as indicated by the dotted outline 65, or it can be adjustably retained in the retracted aside position 65 shown by the outline 66.

In using the word "bristles" in the claims, I wish it 75 to be understood not in the narrow sense only as con-

noting only hairs and only hairs derived from animals or plants, but to include, also, any other natural or synthetic material suitable for brushing the beard and skin of a person in the manner and for the purposes which have hereinbefore been described; and, in using the word "brush" in the claims, I wish it also to be understood as not being limited to an instrument composed of hair bristles, but to include, also, an instrument composed of any other material, natural or synthetic, in filament, or threadlike, or fibrelike form, of any suitable thickness or diameter, which is arranged as are bristles in the ordinary brush and which material and its arrangement are suitable for brushing the beard and the skin of a person in the manner and for the purposes which have hereinbefore been described.

Having described the invention, I claim:

1. In a dry shaver, a casing-handle having a shearing head seating end, a skin-engaging shearing head detachably seated on said seating end, and a hair up-raising brush, having flexible bristles, detachably seated on said seating end and alongside said shearing head, said seating end being adapted to seat said shearing head and said brush in interchanged positions whereby said brush may be disposed alongside either side of said head, and the bristles of said brush being adapted for positive travel on the skin simultaneously with the travel on the skin by said shearing head as said head is engaged on the skin in the shaving operation, said bristles also being adapted for being flexed by the skin in said travel in the direction towards the shearing head when the latter is moved on the skin in the direction in which it trails the brush.

2. In a dry shaver, a casing-handle having a shearing head seating end, a skin-engaging shearing head seated on said seating end, and a hair up-raising brush, having flexible bristles, seated on said seating end and alongside said shearing head, the bristles being secured in said brush in a longitudinal series of tufts and being adapted for positive travel on the skin simultaneously with the travel on the skin by said shearing head as said head is engaged on the skin in the shaving operation, said bristles also being adapted for being flexed by the skin in said travel in the direction towards the shearing head when the latter is moved on the skin in the direction in which it trails the brush.

3. In a dry shaver, a casing-handle having a shearing head seating end, a skin-engaging shearing head seated on said seating end and having a hair-receiving zone, and a hair up-raising brush, having flexible bristles, seated on said seating end and alongside said shearing head, the bristles being secured in said brush in a longitudinal series of tufts and being adapted for positive travel on the skin simultaneously with the travel on the skin by said shearing head as said head is engaged on the skin in the shaving operation and said bristles being adapted for being flexed by the skin in said travel in the direction toward the shearing head, but spaced from the hair-receiving zone thereof, when said head is moved on the skin in the direction in which it trails the brush.

4. In a dry shaver, the combination of a pair of spaced, skin-engaging shearing heads and a hair up-raising brush disposed between said heads, the brush having flexible bristles adapted for positive travel on the skin simultaneously with the travel on the skin by said shearing heads as said heads are engaged on the skin in the shaving operation, either of said shearing heads being adapted to trail the brush in the shaving operation and said bristles also being adapted for being flexed by the skin, in said travel thereon, in the direction towards whichever of said shearing heads trails said brush.

5. In a dry shaver, the combination of a pair of spaced, skin-engaging shearing heads and a hair up-raising brush disposed between said heads, the brush having flexible bristles secured therein in a longitudinal

series of tufts, and the bristles being adapted for positive travel on the skin simultaneously with the travel on the skin by said shearing heads as said heads are engaged on the skin in the shaving operation, either of said shearing heads being adapted to trail the brush in the shaving operation and said bristles also being adapted for being flexed by the skin, in said travel thereon, in the direction towards whichever of said shearing heads trails said brush.

6. In a dry shaver, the combination of a pair of spaced, skin-engaging shearing heads having hair-receiving openings and a hair up-raising brush disposed between said heads, the brush having flexible bristles secured therein in a longitudinal series of tufts, the bristles being adapted for positive travel on the skin simultaneously with the travel on the skin by said shearing heads as said heads are engaged on the skin in the shaving operation, either of said shearing heads being adapted to trail the brush in the shaving operation and said bristles also being adapted for being flexed by the skin, in said travel thereon, in the direction towards, but spaced from the hair-receiving openings of, whichever of said shearing heads trails said brush.

7. In a dry shaver, in combination, a pair of spaced, skin-engaging shearing heads, a hair up-raising brush disposed between said heads, and a side hair up-raising brush in the shaver spaced from the first said brush by a shearing head, the brushes having flexible bristles adapted for travel on the skin simultaneously with the travel on the skin by said shearing heads as said heads are engaged on the skin in the shaving operation.

8. In a dry shaver, in combination, a pair of spaced, skin-engaging shearing heads, a hair up-raising brush disposed in said shaver between said heads, and a side hair up-raising brush in the shaver spaced from the first said brush by a shearing head, the bristles being flexible and being secured in the brushes in longitudinal series of tufts and adapted for travel on the skin simultaneously with the travel on the skin by said shearing heads as said heads are engaged on the skin in the shaving operation.

9. In a dry shaver, in combination, a pair of spaced, skin-engaging shearing heads, a hair up-raising brush disposed between said heads, and a side hair up-raising brush in the shaver spaced from the first said brush by a shearing head, the brushes having flexible bristles secured therein in longitudinal series of tufts, the bristles of said brushes being adapted for travel on the skin simultaneously with the travel on the skin by said shearing heads as said heads are engaged on the skin in the shaving operation and said bristles of the brushes being adapted for being flexed by the skin towards the shearing heads, but spaced from the hair-receiving openings thereof, as said heads are moved on the skin in the direction in which each of said heads trails one of said brushes.

10. In a dry shaver, in combination, a skin-engaging shearing head, a movably mounted hair up-raising brush having flexible bristles for travel on the skin simultaneously with the travel on the skin by said shearing head as said head is engaged on the skin in the shaving operation, means for adjustably spacing said brush laterally from said head with said bristles disposed alongside said head for simultaneous travel on the skin therewith, and means for releasably retaining said brush so adjustably spaced laterally from said head.

11. In a dry shaver, in combination, a skin-engaging shearing head, a movably mounted hair up-raising brush having flexible bristles adapted for travel on the skin simultaneously with the travel on the skin by the shearing head as said head is engaged on the skin in the shaving operation, the bristles of said brush being adapted for being flexed by the skin toward the shearing head, but spaced from the hair-receiving openings thereof, as said head is moved on the skin in the direction in which said head trails said brush laterally, means for adjustably spacing said brush from said head with said bristles disposed alongside said head for simultaneous travel on

the skin therewith, and means for releasably retaining said brush so adjustably spaced laterally from said head.

12. In a dry shaver, in combination, a skin-engaging shearing head, a movably mounted hair up-raising brush having flexible bristles adapted for travel on the skin simultaneously with the travel on the skin by said shearing head as said head is engaged on the skin in the shaving operation, means for adjustably spacing said brush laterally from said head with said bristles of said brush disposed alongside a side of said head for simultaneous travel on the skin therewith during said shaving operation, or for adjustably positioning said brush retracted aside to expose said side of said shearing head, and means for releasably retaining said brush so adjustably spaced laterally from said head or so positioned retracted aside.

13. In a dry shaver, in combination, a skin-engaging shearing head, a movably mounted hair up-raising brush having flexible bristles adapted for travel on the skin simultaneously with the travel on the skin by said shearing head as said head is engaged on the skin in the shaving operation, the bristles being secured in the brush in a longitudinal series of tufts therein and being adapted to be flexed by the skin toward said shearing head, but spaced from the hair-receiving openings thereof, as said head is moved on the skin in the direction in which said head trails said brush, means for adjustably spacing said brush laterally from said head with the bristles of said brush disposed alongside a side of said head for simultaneous travel on the skin therewith during the shaving operation, or for adjustably positioning said brush retracted aside to expose said side of said head, and means for releasably retaining said brush so adjustably spaced laterally from said head or so positioned retracted aside.

14. In a dry shaver, in combination, a skin-engaging shearing head, a hair up-raising brush disposed alongside one side of the head and a movably mounted hair up-raising brush disposed on the opposite side of said head, the brushes having flexible bristles adapted for travel on the skin simultaneously with the travel on the skin by said shearing head as said head is engaged on the skin in the shaving operation, means for adjustably spacing said movably mounted brush laterally from said head with said bristles of said movably mounted brush disposed alongside a side of said head for simultaneous travel on the skin therewith during the shaving operation, and means for releasably retaining said movably mounted brush so adjustably spaced laterally from said shearing head.

15. In a dry shaver, in combination, a skin-engaging shearing head, a hair up-raising brush disposed alongside one side of the head and a movably mounted hair up-raising brush disposed on the opposite side of said head, the brushes having flexible bristles adapted for travel on the skin simultaneously with the travel on the skin by the shearing head as said head is engaged on the skin in the shaving operation, means for adjustably spacing said movably mounted brush laterally from said head with said bristles of said movably mounted brush disposed alongside a side of said head for simultaneous travel on the skin therewith during said shaving operation, or for adjustably positioning said movably mounted brush retracted aside to expose said last side of said shearing head, and means for releasably retaining said movably mounted brush so adjustably spaced laterally from said head or so positioned retracted aside.
16. In a dry shaver, in combination, a pair of spaced, skin-engaging shearing heads, a hair up-raising brush disposed between said heads, side hair up-raising brushes in said shaver spaced from each other by said shearing heads, the three said brushes having flexible bristles adapted for travel on the skin simultaneously with the travel on the skin by said shearing heads as said heads are engaged on the skin in the shaving operation, one of said side brushes being movably mounted, means for adjustably spacing said movably mounted brush laterally from the adjacent shearing head with its bristles disposed alongside a side of said adjacent head for simultaneous travel on the skin with said heads as said heads are engaged on the skin in the shaving operation, or for adjustably positioning said movably mounted brush retracted aside to expose said side of said adjacent head, and means for releasably retaining said movably mounted brush so adjustably spaced laterally from said adjacent head or so positioned retracted aside.
